US00D941291S

(12) **United States Design Patent** (10) **Patent No.:** **US D941,291 S**
Escolin et al. (45) **Date of Patent:** **** Jan. 18, 2022**

(54) **KEYBOARD**

(71) Applicant: **Microsoft Corporation**, Redmond, WA (US)

(72) Inventors: **Timothy G. Escolin**, Seattle, WA (US); **Young Soo Kim**, Bellevue, WA (US); **Scott Schenone**, Seattle, WA (US); **Panos Costa Panay**, Redmond, WA (US); **Ralf Groene**, Kirkland, WA (US); **Brian Min**, Kirkland, WA (US); **Ryan Eugene Whitaker**, Seattle, WA (US)

(73) Assignee: **Microsoft Corporation**, Redmond, WA (US)

(**) Term: **15 Years**

(21) Appl. No.: **29/707,896**

(22) Filed: **Oct. 1, 2019**

(51) LOC (13) Cl. **14-02**

(52) U.S. Cl.

USPC **D14/392**

(58) **Field of Classification Search**

(57) **CLAIM**

The ornamental design for a keyboard, as shown and described.

DESCRIPTION

FIG. 1 is a perspective view of a keyboard showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the keyboard that form no part of the claimed design.

1 Claim, 4 Drawing Sheets
